UNITED STATES PATENT OFFICE.

LEWIS E. CURTIS, OF WARREN, OHIO, ASSIGNOR TO THE YOUNGSTOWN PRESSED STEEL COMPANY, OF WARREN, OHIO, A CORPORATION OF OHIO.

PROCESS OF PRODUCING EXPANDED METAL.

Application filed June 2, 1921. Serial No. 474,506.

To all whom it may concern:

Be it known that I, LEWIS E. CURTIS, a citizen of the United States, and a resident of Warren, in the county of Trumbull and State of Ohio, have invented certain new and useful Improvements in Processes of Producing Expanded Metal, of which the following is a specification.

My present invention relates to improvements upon existing methods of producing expanded metal lathing of the herring bone type, and aims to provide a simple, economical and efficient method which will result in an article having greater stiffness in proportion to the weight of metal.

In order that my invention may be readily understood, reference is made to the accompanying drawings, in which:

Figure 1 is a diagrammatic face view of a metal sheet showing a portion of the sheet unslitted and with the remaining portion illustrating the manner of slitting.

Figs 1^a and 1^b are detail views illustrating the formation of the cutting dies which I preferably use.

Fig. 2 is a diagrammatic sectional view illustrating the method of flattening the sheet and forming longitudinal ribs.

Fig. 3 is a similar view illustrating the manner in which the metal between the rows of slits is angularly displaced relative to the plane of the sheet.

Fig. 4 is a diagrammatic view illustrating the spreading means at the commencement of the spreading operation.

Fig. 5 is a plan view of the sheet of Fig. 4 before being spread.

Fig. 6 is a view of the spread or opened sheet.

Fig. 7 is a plan view of the completed sheet.

In proceeding according to my invention, I take a plain sheet of metal of the desired weight or gauge and feed it intermittently between successively disposed and co-acting pairs of reciprocating dies 2 and 2^a such as shown in Figs. 3 and 4. All the dies of one pair are arranged or inclined so as to slit the sheet on parallel lines to produce in a defined or predetermined area thereof (depending on the extent of die surface desired) spaced parallel rows of slit strands as indicated at 1^a, all inclining in the same direction. Immediately following the action of one set of dies the sheet

is advanced a step and the second set of dies 55 comes into action on said defined or predetermined area, such second set being inclined reversely to the first set and being so disposed as to slit the unslitted portions adjacent to or intervening between the previous rows of 60 slits as indicated at 1^b. I thereby produce a sheet having parallel rows of strands, the strands of any one row inclining in an opposite direction to those of the adjacent row or rows. Narrow strip or unslitted portions 65 1^c intervene between certain of the rows and the sheet has also wider unslitted marginal portions 1^d and intermediate unslitted portions 1^e and 1^f, such marginal and wider intermediate portions being utilized for the 70 formation of the longitudinal ribs in the manner hereinafter described.

It will be understood that I do not limit myself to any particular number of ribs, the arrangement shown of three high ribs 75 and two of lesser height being illustrated as a desirable form.

The dies are preferably shaped so as to deflect one strand while holding the adjoining strand in the plane of the sheet as this 80 facilitates the subsequent flattening of the sheet. The die construction preferred for this purpose is shown in Figs. 1^a and 1^b from which it will be seen that the lower die member 2^a has strand receiving recesses or die cavities *a* and the upper die member male die portions *a'* fitting such cavities; the die face or faces between the male parts *a'* being formed on straight lines parallel with the plane of the sheet as also are the faces of the intervening portions *a²* of die member 2^a.

The sheet may be flattened to bring the deflected strands back into the plane of the sheet in any suitable manner and as a separate step, as by plain faced dies (not shown) or it may be flattened simultaneously with the formation of the longitudinal ribs.

The forming of the ribs can be effectively accomplished by upper and lower reciprocating coacting dies 3 and 3^a having respectively male and female die parts or ribs and grooves 3^b and 3^c for forming the high ribs and also having respectively female and male die parts or grooves and ribs 3^e and 3^f for forming the ribs of lesser height, the high ribs being indicated at 1^x and the ribs of lesser height at 1^y. The dies 3 and 3^a

subject the unslotted portions throughout definite or determined lengths to a swaging action and thus produce the aforesaid ribs.

The next step is to turn or deflect the narrow strips of metal between the rows of strands into a position inclined to the plane of the sheet so as to displace the rows of strands in the direction they are to move, or cause them to lie in planes at an angle to the plane of the sheet preparatory to opening out the sheet, and this I may accomplish by the use of die members 4 and 4^a, preferably reciprocating, such dies having their faces provided with longitudinal ribs or grooves of the shape clearly shown in Fig. 3, and having also coacting ribs and grooves to fit the previously formed longitudinal ribs of the sheet by which the sheet will be properly positioned and held during the closing of the dies.

Thereafter the sheet is spread or opened out and this I accomplish by carrying the marginal portions bodily away from each other.

This is preferably done by supporting the sheet upon a suitable table or member 5 and providing transversely movable slides having projection portions 6^a to fit the hollow portions of the marginal ribs, and coacting gripper members 7 having rib receiving grooves 7^a. The slides and coacting grippers are moved simultaneously in opposite directions by suitable means such as links 8 eccentrically connected to discs 9 or their equivalent, which may be rotated by any suitable means (not shown). The sheet before expanding is shown in plan view in Fig. 6 and in section in Fig. 3, while the expanded sheet is shown in section in Fig. 5 and in plan in Fig. 7.

In expanding a three high rib sheet, I prefer to engage the central rib by fixed die members 10 and 10^a but for a sheet containing four or more ribs a plurality of slides and grippers would be used moving at differential speeds in opposite directions.

It will be understood that the various steps above described are preferably all carried out intermittently, the sheet or sheets being fed forward when the dies are separated and held stationary while the dies are acting, the same remarks applying to the action of the grippers.

It will also be understood that I do not limit myself to the means shown in the drawings for carrying out the method, such means being shown diagrammatically as representative of any suitable means.

Having thus described my invention, what I claim is:

1. The herein described method of producing expanded metal which consists in simultaneously forming in defined areas, a plurality of rows of longitudinally alined slits in a sheet to form parallel rows of in-

clined strands, inclining the strands of each row with relation to the plane of the sheet while maintaining them as a whole in said plane, and thereafter drawing the margins of the sheet in opposite directions 70 in the plane of the sheet.

2. The herein described method of producing expanded metal which consists in simultaneously forming a plurality of longitudinally alined slits in a sheet to form 75 parallel rows of inclined strands, subsequently further slitting the sheet to form other rows of strands inclined reversely to said first named strands, inclining such strands with relation to the plane of the 80 sheet while maintaining them as a whole in the plane of the sheet, and thereafter drawing the margins of the sheet in opposite directions.

3. The herein described method of producing expanded metal which consists in intermittently feeding a metal sheet, simultaneously forming in successively defined areas a plurality of longitudinally alined slits to produce parallel rows of inclined 90 strands, thereafter similarly slitting defined areas to produce adjacent rows of reversely inclined strands, and finally opening out the sheet.

4. The herein described method of producing expanded metal which consists in intermittently feeding a metal sheet, successively slitting defined areas to produce parallel rows of inclined strands, thereafter successively slitting defined areas to 100 produce adjacent rows of reversely inclined strands, deflecting such strands into angular relation to the plane of the sheet, and thereafter opening out the sheet.

5. The herein described method of producing expanded metal which consists in intermittently feeding a metal sheet, successively slitting defined areas to produce parallel rows of inclined strands, thereafter successively slitting defined areas to produce adjacent rows of reversely inclined strands, successively deflecting the strands of each of such defined areas into angular position relative to the plane of the sheet, and finally successively drawing bodily 110 apart the edges of the sheet.

6. The herein described method of producing expanded metal which consists in simultaneously forming a plurality of longitudinally alined slits in a sheet to produce 120 parallel rows of inclined slits, the slits of one row being inclined reversely to the slits of the adjacent rows, and said sheet having unslotted margins, successively subjecting defined lengths of said margin to a swaging operation to produce longitudinal ribs, and thereafter successively grasping such ribbed portions and drawing them bodily in opposite directions.

7. The herein described method of pro-

ducing expanded metal which consists in simultaneously forming a plurality of longitudinally aligned slits in a sheet to produce parallel rows of inclined slits, the slits of one row being inclined reversely to the slits of the adjacent rows, and said sheet having unslotted marginal and intermediate portions, successively swaging said unslotted portions to produce longitudinal ribs, and finally successively grasping said ribbed portions and displacing them relative to each other in the plane of the sheet.

8. The herein described method of producing expanded metal which consists in intermittently feeding a metal sheet, successively simultaneously forming in defined areas a plurality of rows of aligned slits to

produce parallel rows of strands all inclining in one direction, thereafter similarly slitting adjoining portions of said defined areas to 20 produce other rows of reversely inclined strands, successively deflecting all of the strands of such defined areas into planes inclined to the plane of the sheet, marginal portions and intermediate portions of the 25 sheet being left unslotted, successively swaging determined lengths of said unslotted portions to produce longitudinal ribs, and finally successively moving the marginal ribbed portions in opposite directions in the plane 30 of the sheet.

In testimony whereof, I affix my signature.

LEWIS E. CURTIS.
